FIG. 1

FIG. 2

INVENTOR.
HENRY D. GLASS

BY Henry D. Glass

UNITED STATES PATENT OFFICE

141,546

DESIGN FOR A PLAYING BALL

Henry D. Glass, Akron, Ohio, assignor to
Selberling Latex Products Company, Barberton,
Ohio, a corporation of Ohio

Application February 19, 1941, Serial No. 99,104

Term of patent 14 years

(Cl. D34—15)

To all whom it may concern:

Be it known that I, Henry D. Glass, a citizen of the United States, residing at Akron, in the county of Summit and State of Ohio, have invented a new, original, and ornamental Design for Playing Ball, of which the following is a specification, reference being had to the accompanying drawing, forming part thereof.

I claim:

The ornamental design for a playing ball, as shown.

HENRY D. GLASS.
